SELF LOCKING PLIERS

Dain W. Heald, Temple City, Calif.

Application December 23, 1955, Serial No. 555,099

6 Claims. (Cl. 81—339)

This invention relates to pliers and particularly to a self-locking pliers.

An object of this invention is to provide a convenient hand tool which is particularly adapted to be used as pliers which, when tightened on an object, remains locked and tightened on the object, even though no further force is exerted on the handle, which cannot be unlocked by spreading force exerted on the jaws, and which can easily be opened by pulling the handles apart.

This invention is carried out by providing a pair of jointed jaws, said jaws being pivoted together, each jaw having a lever attached thereto on the same operative side of the pivot so that the levers and jaws are not crossed. Then, spreading the levers pushes the jaws together. A pair of handles are pivoted to each other at a fulcrum, with the fulcrum disposed between the two said handles so that squeezing adjacent ends of the handles together moves the ends apart which are on the other side of the fulcrum. An end of each handle is pinned to one of the levers of the pliers.

One of said handles is provided with a cam surface on the same side of the fulcrum as the jaws, and the other handle is provided with a channel which accommodates a slidably wedge and a pin adapted to be forced against the wedge by the cam.

A feature of the invention resides in an interconnection between the handle having the cam, and the wedge, whereby opening of the handles pulls the wedge from beneath the pin.

A related feature of this invention resides in providing the handle with the cam in two segments, the segment to which the aforesaid interconnection is attached being flexible relative to the other segment of the handle, whereby the wedge may be moved substantially independently of the cam.

The above and other features of this invention will be fully understood from the following detailed description and the accompanying drawings of which:

Fig. 1 is a plan view, partly in cross-section, of a self-locking pliers according to the invention, showing the pliers in an open, or released, condition;

Fig. 2 is a plan view, partly in cross-section, of the pliers in the closed, or gripping condition;

Fig. 3 is a cross-section taken at line 3—3 of Fig. 2; and

Fig. 4 is a fragmentary view, partly in cross-section, of an optional form of the invention.

In Fig. 1, a pair of self-locking pliers 10 is shown in an open, or released, position. Jaw means 11, comprises a first jaw 12 having a lever 13, and second jaw 14 having a lever 15. The jaws are joined by a pivot 16 which may simply be a pin. A land 17 on each jaw is joined by the pivot, so that the pivot is between the jaws and levers, with the individual jaw-lever combinations uncrossed. Therefore, the jaws will be opened by pressing the levers together, and will be closed by pulling the levers apart.

A first handle 18 has a U-shaped cross-section (see

2

Fig. 3) so as to provide a channel 19 between the legs 20 of the cross-section. A block 21 is placed in the channel, spaced from the bight 22 of the cross-section.

A locking wedge 23 is slidable in the channel 19 between the bight, legs and block. This wedge has a locking surface 23a which makes an angle θ with its base 24. The base 24 slides on the bight of the channel.

A locking pin 25 extends into the channel adjacent the end of the block nearest the jaws, and has a locking surface 26 which makes an angle with the base 24 of the wedge which is preferably equal to θ . The locking pin can thus be shoved against the locking wedge so that the locking surfaces contact each other.

A second handle 27 comprises two segments: a forward segment 28, and a rear segment 29. The forward segment is U-shaped in cross-section, and folds around a fulcrum block 30. Fulcrum block 30 has an ear 31 with a hole therein which matches holes in the legs 20 of the first handle. A fulcrum is formed between the two handles by placing a fulcrum pin 32 through these holes. Thus, the fulcrum is between both of the handles, and intermediate the ends of both of them, so that squeezing a pair of adjacent ends moves the other ends apart. Rivets 33 hold the fulcrum block in the forward segment of the second handle.

The fulcrum block has an extension 34 which projects beyond the rear end of the forward segment, which extension has a round hole 35 and an elongated hole 36. Hole 36 is preferably, although not necessarily, farther from the forward segment than the round hole 35.

A cam 37 is incorporated in the fulcrum block on the side of the fulcrum nearest the jaws, so that the cam bears down on the top of the locking pin to force the locking surface of the pin against the locking surface of the wedge. The cam withdraws from the locking pin as the forward segment of the second handle moves away from the first handle, to close the jaws, and moves against the locking pin when the forward segment moves toward the first handle, to open the jaws.

The rear segment 29 of the second handle is attached to the extension 34 of the fulcrum block by pins 38 and 39 in holes 35 and 36, respectively. The rear segment therefore can pivot slightly around pin 38. Springing means, which may be such as a coil spring 40, are attached to extension 34 and to the rear segment so as to normally draw the rear segment inward toward the first handle.

Pins 41 and 42 respectively join the first handle to lever 13, and the forward segment of the second handle to lever 15.

A link 43 is pivotally joined to the locking wedge, and to a block 44 attached to the rear segment of the second handle, by pins 45 and 46, respectively. The preferred arrangement of pivot 16, fulcrum, and pin 46 is shown in Fig. 2, where with the jaws tightly clamped together, these three elements are in line. While these elements are aligned in the embodiment of Fig. 2, it will be understood that this is not an essential limitation, because they may also be out of line and still have operative properties.

Slot 47 in the link allows some free play at pin 46.

Fig. 4 illustrates a direct connection between link 43 and rear segment 29, without the intervention of the block 44, where the pivot, fulcrum and pin are out of line. The pivot, fulcrum and pin 48 will not be in a single line, but the pliers will work nearly as well. Slot 49 permits some free play at pin 48.

It is evident that link 43 may have different configurations, and make various angles with the handles of the pliers. The handles themselves may have various configurations. Furthermore, the length and angles of locking pin 25 and wedge 23 may be varied to suit the

requirements of a given plier structure. The pins 45, 46, 32 and 16 may also be repositioned to suit the requirements of a given plier design.

The jaw design shown is suitable for many uses, but is intended to be merely exemplary of a pair of plier jaws. Various well-known jaws may be substituted for these, such as cutters, wire twisters, sockets for welding rods, and water pumps. These are all well-known jaws which require no illustration or further discussion here. In addition, means may be provided for maintaining parallel jaw action in accordance with well-known jaw construction.

The operation of these pliers will now be described. Starting with the pliers in the open position shown in Fig. 1, the handles are squeezed together. This spreads pins 41 and 42 apart, and moves jaws 12 and 14 together to clamp on some object such as a nut, for example.

During this closing movement, the rear segment 29 of the second handle will be in line with the first segment, and will force link 43 to move the locking wedge 23 toward the jaws. Since the cam 37 is on the opposite side of the fulcrum from the squeezing action, the cam is moved away from channel 19, and this permits locking pin 25 to move away from the advancing locking surface 23a of the locking wedge. The various dimensions of the cam, the link, and the angle θ will be chosen so that the advance of locking surface 23a is not so rapid that the cam does not permit the locking pin to back off. Otherwise, the device might tend to lock before the jaws are tightened on the object.

However, the provision of the second handle in two segments does result in a significant dimensional flexibility, for as the handles are squeezed together, there is a force against the cam which tends to move the extension 34 toward the first handle. Were the second handle in a single piece, this would, of course, tend to jam the locking wedge even more tightly against the locking pin, and the relative dimensions of the device would be fairly critical. However, with the slight pivoting allowed the rear segment 29, the said movement of the extension 34 can be accomplished independently of the rear segment of the handle, the pin 39 simply moving in elongated hole 36. This enables the locking pin and cam to back off from the wedge slightly, and then the jaws can continue to close.

When the jaws firmly grip the object, then there can be no further movement of the cam, and the link 43 shoves the wedge firmly under the locking pin, with pin 39 solidly against the inner wall of elongated hole 36. The pliers are now locked on the object. Such a condition is shown in Fig. 2, where the jaws are simply closed on one another.

Now if an effort be made to pry the jaws apart, or press the handles together on the jaw side of the fulcrum, the cam will simply press down on the locking pin, which thereupon presses on the wedge. Any suitable angle θ may be used, but in practice a gentle slope is preferred, angle θ preferably being in the range from 25° to 35°, 35° being the presently preferred value, and the effect is simply to lock the locking wedge in place, rather than slide it, and the jaws are thus held closed. However, angles θ less and greater than 25°-35°, respectively, are within the scope of this invention. The play in the second handle prevents any slight movement of the handles from withdrawing the locking wedge by pulling on link 43.

When the pliers are to be opened, the condition shown in Fig. 1 results. Pulling the rear ends of the handles apart withdraws the wedge by means of link 43, and this permits the cam to press the locking pin toward the locking wedge. However, the wedge is pulled from beneath the locking pin at least as fast as the pin approaches surface 23a, so that the pliers can be opened.

The provision of the second handle in two segments

eases the opening action, and also makes the relative dimensions less critical, inasmuch as, if the cam presses the locking pin so firmly against the locking wedge that the wedge tends to be impeded from being withdrawn, the rear segment can pivot around pin 35 and move the wedge out from beneath the locking pin without moving the cam. Then, when the wedge is slightly moved, the cam can again move, and the jaws will be released.

10 The slots 47 and 49 allow some further flexibility of the link and wedge action.

Tests have been made to determine the operability of this device and it has been found that, utilizing 6 inch handles, and a 1 inch jaw, a light hand squeeze on the handles results in a grip on an object which has not been dislodged, even by placing the front ends of the handles in a vise and applying an extremely great force thereto. In fact it has been found that the tool will be destroyed before the jaws can be pried apart.

15 20 This invention is not to be limited by the embodiments shown in the drawing and described in the description, which are given by way of illustration and not by way of limitation, but only in accordance with the scope of the appended claims.

25 I claim:

1. A self-locking pliers, comprising: two jaws, two levers, each of said levers being integral with a different one of said jaws; a pivot joining said jaws, each jaw and its integral lever being on a single side of the pivot,

30 35 whereby spreading the levers moves the jaws together; a first handle having a channel therein; a second handle; said handles being pivotally joined by a fulcrum, said handles being on opposite sides of the fulcrum whereby spreading one pair of adjacent ends of said handles moves the other pair of adjacent ends together, one pair of adjacent ends of the handles being attached to the levers, each lever being attached to a different one of said handles, whereby pressing the handles together on the end of the handles remote from the jaws moves the jaws together; a wedge slidably fitted in said channel; a sloping locking surface on said wedge; a locking pin slidably disposed in said channel; a locking surface on said locking pin adapted to engage said locking surface on the wedge; a cam on said second handle engaging the

40 45 locking pin to force it toward the wedge, said locking pin and cam being on the side of the fulcrum nearest the jaws; and a link attached to and interconnecting the wedge and the second handle on the opposite side of the fulcrum from the jaws; whereby pressing together the ends of the handles remote from the jaws closes the jaws, and forces the locking wedge under the locking pin to prevent the jaws from opening, and whereby pulling apart said handle ends pulls said locking wedge from beneath said locking pin to permit the jaws to open.

50 55 2. Apparatus according to claim 1 in which the locking surface of the wedge makes an angle of between 25° and 35° with the base of the wedge.

3. Apparatus according to claim 1 in which the locking surface of the wedge makes an angle of approximately 60 65 35° with the base of the wedge.

4. A self-locking pliers, comprising: two jaws, two levers, each of said levers being integral with a different one of said jaws; a pivot joining said jaws, each jaw and its integral lever being on a single side of the pivot, whereby spreading the levers moves the jaws together; a first handle having a channel therein; a second handle; said handles being pivotally joined by a fulcrum, said handles being on opposite sides of the fulcrum whereby spreading one pair of adjacent ends of said handles moves the other pair of adjacent ends together, one pair of adjacent ends of the handles being attached to the levers, each lever being attached to a different one of said handles, whereby pressing the handles together on the end of the handles remote from the jaws moves the

jaws together; a wedge slidably fitted in said channel; a sloping locking surface on said wedge; a locking pin slidably disposed in said channel; a locking surface on said locking pin adapted to engage said locking surface on the wedge; a cam on said second handle engaging the locking pin to force it toward the wedge, said locking pin and cam being on the side of the fulcrum nearest the jaws; and a link attached to and interconnecting the wedge and the second handle on the opposite side of the fulcrum from the jaws; whereby pressing together the ends of the handles remote from the jaws closes the jaws, and forces the locking wedge under the locking pin to prevent the jaws from opening and whereby pulling apart said handle ends pulls said locking wedge from beneath said locking pin to permit the jaws to open; said second handle comprising two parts: a forward segment adjacent the jaws, and a rear segment, said rear segment being pivotally mounted to said forward segment, said link being rigid and attached to the said rear segment whereby the wedge can be moved by the rear segment 20

without moving the forward segment of said second handle.

5. Apparatus according to claim 4 in which said link has a slot therein, and is joined by pins to the wedge and 5 to the rear segment, one of said pins projecting into said slot so as to be slidable therein and permit free movement of said second handle independently of movement of the wedge.

6. Apparatus according to claim 4 in which the rear 10 segment is mounted to the forward segment by means of a pair of pins, one of said pins being laterally shiftable in one of said segments.
